AUTOMATIC FIREARM

Filed Nov. 27, 1929

INVENTOR:

BY Karl Heinemann

Karl Heinemann

ATTORNEY.

UNITED STATES PATENT OFFICE

KARL HEINEMANN, OF DUSSELDORF, GERMANY, ASSIGNOR TO RHEINISCHE METALLWAAREN- UND MASCHINENFABRIK, OF DUSSELDORF-DERENDRÖF, GERMANY, A CORPORATION OF GERMANY

AUTOMATIC FIREARM

Application filed November 27, 1929, Serial No. 410,201, and in Germany September 27, 1929.

Automatic firearms are usually equipped with interchangeable magazines, so that, when a magazine is empty, a full one can be substituted. According to the present invention, the gun is also constructed to receive interchangeable magazines, but is also provided with a mechanism, which is old in itself, to automatically secure the breech block in the open position when the magazine is empty, and with an opening in the casing to introduce filled cartridge container, such as a clip, in front of the magazine mouth. In this way, ammunition can be supplied to the weapon either by the introduction of a freshly-filled magazine or by filling the magazine already in the gun directly from cartridge clips, so that interchangeable magazines or only strip ammunition are available for use according to the existing conditions. The locking bolt, in the latter case, prevents any premature closing of the opened breech, so that the recharging of the magazine in the gun can proceed without interference.

An embodiment of the invention is illustrated in the accompanying drawings, in which:

Figure 1 is a longitudinal sectional plan view, and

Fig. 2 is a partial side elevation showing the shell ejector opening.

In the gun casing *a*, a cartridge magazine *b* is laterally inserted and this magazine is locked against displacement by the bolt *b*³, in the usual way. A nose *b*² on the slide *b*¹ of the emptied magazine holds the longitudinally-slidable breech block *c* in the open position. The spring-pressed magazine lock-bolt *b*³ is so connected to a second breech-block latch, slidable by the hand piece *b*⁴, that, in the position illustrated, the bolt *b*³ holds the magazine *b* immovably, while the breech lock *b*⁵ is released, and, in the second position of the hand latch *b*⁴, both locks *b*³ and *b*⁵ are operative to hold the breech open and the magazine locked; finally, when the hand latch *b*⁴ is thrown up into a third position, only the breech block *c* is locked against forward movement by the lock bolt *b*⁵, while the bolt *b*³ has released the maga-

zine *b* for removal from the gun. The shell ejector *d* is mounted in the casing *a*, the breech block *c* having a longitudinal slot *c*' in which said ejector slides. In the head of the breech block is the transversely movable, 55 spring-pressed claw *e*, which can be swung outwardly, as usual, by a longitudinally-movable slide *e*' at the end of the back travel of the breech block to disengage the shell, drawn out of the barrel by said block. 60

The supply of ammunition to the gun can be made by interchanging the magazine *b*. When the latter is empty, its slide *b*' has engaged the breech block *c* in the open position. By swinging the hand latch *b*⁴, the magazine being still locked, the bolt *b*⁵ is first moved into the rest provided in the block *c* and then the lock bolt *b*³ is retracted from behind the holding nose of the magazine, which can now be removed, whereupon the bolt *b*⁵ becomes operative to hold the breech retracted, until a fresh-filled magazine has been inserted in the gun. Only after this locking by *b*³ does the bolt *b*⁵ release the breech-block, which then slides 70 forwardly and feeds the first shell from the magazine into the barrel. 75

The foregoing described combined breech and magazine lock, which, when a new magazine is to be substituted, only permits the 80 breech to move forwardly after the insertion and locking of the new magazine, is also important in connection with the second type of ammunition supply by cartridge containers or clips. In this case, the empty 85 magazine *b* remains in the locked position in the gun, and the breech block *c* is held retracted by the slide *b*'. Then a clip *f*, filled with cartridges *g*, is inserted through the long shell ejector opening *a*' opposite 90 the magazine mouth in the casing, the fork-shaped front end *e*² of the slide *e*', on the breech head serving for such insertion. In the inserted position, the clip *f* engages behind a nose *d*' of the ejector *d* and thereby 95 prevents the breech block from sliding forwardly, after the shells, conveyed from the clip into the magazine *b* by finger pressure, have pushed the slide *b*' back from the breech head. By the drawing out of the 100

emptied clip *f*, the breech *c* slides forwardly and inserts a shell into the barrel.

But also when the magazine *b* holds more shells than are carried by a clip, or when the former still contains a number of shells, the hand latch *b*⁴ can be placed in its central position, the breech block *c* being retracted, so that the bolt *b*³ holds the magazine locked and the bolt *b*⁵ holds the breech locked.

10 Then the breech remains held in rear position under tension, after the slide *b*' is out of breech-locking position, and the inserted clip *f* does not have to serve as such lock. The magazine *b* can then be filled with several cartridge clips introduced successively.

15 I claim as my invention:—

1. An automatic firearm comprising a casing having a recess therein; a breech block in the casing; a removable magazine associated with the casing; and means for automatically retaining the breech block in opened position when the magazine is empty, said recess being in front of the magazine mouth and being adapted for the 25 insertion of a cartridge container so that ammunition can be supplied to the firearm either by changing the magazine or by filling the magazine in the firearm with cartridge containers.
2. An automatic firearm comprising a casing having a recess therein; and a removable magazine associated with the casing opposite to the recess, said recess being adapted for the insertion of a cartridge clip so 35 that ammunition can be supplied to the firearm by the removable magazine or said magazine, in its position in the casing, can be filled with ammunition from a cartridge clip.
3. In a magazine gun, the combination 40 with the casing and retractable breech block, of means acting automatically to hold said block retracted when the magazine is empty; and an additional magazine and 45 breech block lock comprising cooperating members adapted to lock the magazine alone or the breech block alone or both the magazine and breech block.

In testimony whereof, I affix my signature.

KARL HEINEMANN.
